UNITED STATES PATENT OFFICE.

GEORGE B. KELLY, OF BOSTON, MASSACHUSETTS.

MECHANICAL MUSICAL INSTRUMENT.

SPECIFICATION forming part of Letters Patent No. 242,419, dated May 31, 1881.

Application filed February 19, 1881. (No model.)

To all whom it may concern:

Be it known that I, GEORGE B. KELLY, of Boston, in the county of Suffolk and State of Massachusetts, have invented certain new and useful Improvements in Mechanical Musical Instruments, of which the following is a specification.

My invention relates to mechanical musical instruments in which wind-sound-producing devices are controlled in their operation by a perforated music-sheet traveling over a rest in which are ducts leading to the said sound-producing devices.

One object of my invention is to provide a simple and desirable means for holding the music-sheet tightly down upon the rest, so as to prevent any leakage of air between the music-sheet and rest; and another object is to provide for automatically closing the air-ducts in the rest as the end of the music-sheet leaves the instrument, so as to prevent discordant sounds produced from the continued operation of the bellows when all the reed-ducts are open.

The invention consists in the combination, in a musical instrument to be operated by a traveling music-sheet, with the rest for the music-sheet, and a roller or rollers arranged on one side thereof for drawing the music-sheet over the rest, of a non-rotary drag-bar arranged upon the side of the rest opposite said roller or rollers, and under which the music-sheet passes, and which, by its friction upon the music-sheet and by holding it down, retards the latter sufficiently to cause it to be drawn tightly over the rest. With said rest, roller or rollers, and drag-bar are preferably combined springs for impelling the drag-bar down upon the music-sheet.

The invention also consists in the combination, in a musical instrument adapted to be operated by a traveling music-sheet, of a rest for the music-sheet containing air-ducts, a damper or cut-off arranged above said air-ducts, and means to be acted upon by the music-sheet for holding said damper or cut-off elevated above the rest, and preferably springs for impelling said damper or cut-off downward to close all the air-ducts when the end of the music-sheet travels beyond the means upon which it acts to hold the damper or cut-off elevated. I also preferably combine with the

rest, damper, or cut-off, and the means acted upon by the music-sheet the aforesaid drag-bar and springs for impelling it downward.

In the accompanying drawings, Figure 1 55 represents a plan of an instrument embodying my invention, certain parts of the case being omitted for the sake of exhibiting the parts beneath; and Fig. 2 represents a transverse section thereof upon the dotted line *xx*, Fig. 1. 60

Similar letters of reference designate corresponding parts in both the figures.

A designates the case of the instrument, and A' designates stretchers or bearers extending across the instrument and serving to support 65 the top board, B, which rests upon and is secured to them. The said top board is composed, as shown, of two pieces or strips, and cross-bars B' uniting them. In the top board, B, is a rest, C, which is constructed to receive 70 reeds *a*, and has air-ducts *a'* extending to the top of the rest and communicating with the atmosphere. The reeds *a* are here arranged to be operated by pressure; but, if desirable, they might be operated by exhaustion, or pipes 75 or other wind-sound-producing devices might be substituted for the reeds.

D designates an expandible receiver or pressure wind-chest, with which all the reed-ducts 80 *a'* communicate, and which is supplied with air under pressure by two pairs of bellows, D' D², arranged upon opposite sides of said reservoir or wind-chest, one bellows of each pair being upon one side of the receiver, and the other bellows of the pair upon the other side 85 thereof.

E designates the perforated music-sheet, adapted to travel over the rest C, and F F' 90 designate lower and upper feed-rolls, between which the sheet is passed, and by the turning of which it is fed forward. If desirable, in lieu of the two feed-rolls, a single roll might be arranged in their place and the music-sheet connected at one end to it, so as to be wound upon it in playing. The shaft of the lower feed-roll, 95 F, constitutes also the means for driving the bellows in this example of my invention, and is provided with a hand-crank, G, for turning it, and with two other cranks, *b*, represented as set at right angles to each other. The bellows D' D² of each pair are connected by a link, H, so as to work simultaneously, and said 100

link is provided with an upwardly-projecting arm, *c*, which is connected with one of the cranks *b* by a connecting-rod or pitman, *H'*. It will thus be seen that one bellows of each 5 pair is filling with air while the other is discharging into the wind-chest, and that as the cranks *b* are set at right angles to each other the pairs of bellows are operated one after the other, thus providing for a continuous supply 10 of air to the wind-chest.

The damper or cut-off which I employ consists of a bar, *I*, arranged immediately over the reed-ducts *a'*; and *J* designates a second bar arranged upon one side of and near to the 15 rest *C*, and parallel with the damper *I*, to which it is rigidly connected by arms or cross-bars *d*, as seen clearly in Fig. 1.

The damper *I* and bar *J* are provided at each end with arms *e*, which are bent at *f* to form 20 pivots or fulcrums upon which the damper and bar may be swung upward to raise them above the top of the rest *C*. The two arms *e* and their pivots or fulcrums *f* are here shown as composed of a single piece of wire which is 25 carried around the front edge of the damper *I* and fits in a longitudinal groove therein, and one end of said wire is continued beyond the pivot or fulcrum *f* and extends transversely to the pivot or fulcrum, so as to form a lever 30 or hand-piece, *g*, which may be depressed in order to raise the damper *I* and bar *J*.

When not raised by the hand-piece *g*, and before the music-sheet *E* is inserted, the damper *I* and bar *J* are impelled downward to tightly 35 close all the air-ducts *a'* in on the rest *C* by springs *h*, fixed at one end in the cross-bars *B'*, and resting at the other end in grooves *h'* in the bar *J*, whereby their free ends are held against displacement.

40 In order to retard the travel of the music-sheet and increase the friction thereon, I have shown a drag, *K*, also composed of a non-rotary bar arranged parallel with the damper *I* and its attached bar *J*, but entirely independent of and separate from said damper and bar. The drag-bar *K* is impelled downward by 45 springs *i*, which are independent of the springs *h*, which act upon the bar *J*, and is adapted to hold the music-sheet *E* against an adjacent portion of the top board, *B*, and thus retard its movement or produce a drag upon it. As clearly 50 shown in Fig. 1, the arms *e* project under the ends of the drag *K*, and when the hand-piece *g* is depressed to raise the damper *I* and bar *J* the said arms will act upon the drag *K* and raise it also. The notches *j* in the drag *K* are, however, so deep (as shown in dotted outline in Fig. 2) that the arms *e* will not act upon the drag *K* to raise it until the damper *I* and 55 bar *J* have been lifted somewhat, when a further downward movement of the hand-piece *g* will raise the damper *I*, the bar *J*, and the drag *K*.

When a music-sheet is to be inserted, the 60 hand-piece *g* is depressed sufficiently to permit of the music-sheet being passed under the drag

K, the bar *J*, and under the damper *I*, and between the feed-rolls *F F'*. The lower feed-roll, *F*, then being turned by the hand-crank *G*, the music-sheet is drawn forward, and when the 70 hand-piece *g* is released the drag *K* descends upon and holds the music-sheet against the rest, and as the rollers *F F'* are turned the music-sheet is drawn tightly over the rest. At the same time the damper *I* and bar *J* are impelled downward by the springs *h*; but before 75 the damper *I* descends far enough to touch the music-sheet the bar *J* rests upon the music-sheet, and as the latter is drawn tightly between the feed-rollers *F F'* and the drag *K* it 80 holds the damper *I* in an elevated position, the bar *J* being the means through which this is effected. As soon as the back end of the music-sheet passes from under the drag *K* there is no tension upon the sheet, and it readily yields 85 under the bar *J*, permitting the damper *I* to descend upon the rest, thus preventing any air from leaking under the music-sheet through the air-ducts *a'*, and as soon as the music-sheet passes the rest the damper tightly closes all 90 the ducts and prevents any discordant sounds produced by the bellows being operated while all the air-ducts are open.

L designates a bar extending across the instrument, between the damper *I* and the feed-rolls *F F'*, and having its lower edge, which is 95 adjacent to the damper, beveled or inclined, so that when the music-sheet is inserted under the damper its edge will be prevented from curling up and passing over both feed-rolls, 100 and will be directed between the rolls.

The top of the case *A* is open, and is provided with swell-covers *A²*, hinged at *k*, and adapted to be swung upward to open, as shown in Fig. 2. In the adjacent edges of these swell-covers are notches *l*, which receive the ends of a rod or wire, *m*, which is secured in a lever, *n*, hinged at one end, and adapted to be depressed by a push piece or button, *o*, extending through the top of the case. By pushing 105 the piece or button down the ends of the rod or wire *m* act upon the edges of the swell-covers *A²*, and thus raise them both. When released they close or return to the position shown in dotted outline in Fig. 2 by their 115 weight.

What I claim as my invention, and desire to secure by Letters Patent, is—

1. In a mechanical musical instrument adapted to be operated by a traveling music-sheet, 110 the combination of a rest, a roller or rollers upon one side of said rest for drawing the music-sheet forward, and a non-rotary drag-bar upon the other side of said rest under which the music-sheet passes, substantially as specified. 115

2. In a mechanical musical instrument adapted to be operated by a traveling music-sheet, 120 the combination of a rest for the music-sheet, a roller or rollers upon one side of said rest for drawing the music-sheet forward, a non-rotary drag-bar upon the other side of said 125 rest under which the music-sheet passes, and

springs for impelling said drag downward, substantially as specified.

3. In a mechanical musical instrument adapted to be operated by a traveling music-sheet, 5 the combination of a rest for the music-sheet containing air-ducts, a damper or cut-off arranged above said rest, and means acted upon by the music-sheet for holding said damper or cut-off elevated above the rest, substantially 10 as and for the purpose specified.

4. In a mechanical musical instrument adapted to be operated by a traveling music-sheet, the combination of a rest for the music-sheet containing air-ducts, a damper or cut-off arranged above said rest, means acted upon by 15 the music-sheet for holding said damper or cut-off elevated above the rest, and springs for impelling said damper or cut-off downward

when released by the music-sheet, substantially as specified.

5. In a mechanical musical instrument adapted to be operated by a traveling music-sheet, the combination of a rest for the music-sheet containing air-ducts, a damper or cut-off arranged above said rest, a cross-bar under which 25 the music-sheet is to pass, arranged parallel with and connected with said damper or cut-off so as to hold the latter elevated, substantially as specified.

6. The combination of the rest C, a feed roller 30 or rollers, the damper I and its connected cross-bar J, and the drag K, substantially as specified.
